UNITED STATES PATENT OFFICE.

CECIL EDWARD DILLISTONE, OF OWEN SOUND, ONTARIO, CANADA.

FOOT-OPERATED LATCH FOR DOORS AND THE LIKE.

Application filed November 12, 1921. Serial No. 514,820.

To all whom it may concern:

Be it known that I, CECIL EDWARD DILLISTONE, a subject of the King of Great Britain, residing in Owen Sound, county of Grey, Province of Ontario, Canada, have invented certain new and useful Improvements in Foot-Operated Latches for Doors and the like, of which the following is a specification.

10 My invention relates to improvements in foot-operated latches for doors and the like, and the object of my invention is to provide means particularly adapted for use in connection with the doors of cold-storage rooms and refrigerators, (which doors are of a heavy type), so that the door will not have to be opened before the load is picked up, thereby enabling the door to be kept closed until the load carrier is in position to 20 enter the chamber or refrigerator, thereby conserving the cold air therewithin because of the shorter length of time required to keep the door open, than when the same is opened by hand before the load is picked up, 25 thereby enabling me to maintain a more uniform degree of temperature within the said chamber or refrigerator and consequently conserve in the consumption of ice, and in the following specification I shall describe 30 my preferred form of construction, and a modification thereof, and what I claim as new will be set forth in the claim forming part of this specification.

Fig. 1 is a front elevation of portion of a 35 door and frame, showing my preferred form of contrivance mounted wholly on the outside. Fig. 2 is a front elevation of portion of a door and frame, showing my modified form of a contrivance mounted, in part, 40 within the door-jamb casing, and Fig. 3 is a vertical section through the door-jamb casing showing my particular manner of mounting the latch-lifter-rod in place.

In the drawings, like characters of reference refer to the same parts.

45 A is portion of a door leading into a cold-storage chamber or a refrigerator, and pivoted thereto as at B is any suitable type of latch C, which co-acts with a keeper 4 carried by the door-jamb casing 5 in any suitable manner, to maintain the door closed.

50 6 is the latch-lifter-rod associated with the door-jamb casing 5, exteriorly, and having its upper end 7 positioned underneath the latch C. 8 is a foot-operating lever pivoted

5 at 9 to the bracket 10, and the end 11 of this lever co-acts with the lower end of the rod 6 to actuate the same.

By pressing down upon the lever 8 by the foot as shown by arrow, the rod 6 is lifted, 60 thus moving the latch C out of engagement with the keeper 4, and so permit the door to open. Any suitable means may be employed to support the rod 6 such as keepers 12 carried by the door-jamb casing 5.

65 The weight of the rod 6 will return the lever 8 to normal position after the foot is released, and so will permit the latch to engage with the keeper 4 when the door is closed.

70 As is usual in practice, the keeper 4 is located quite close to the door A, and it will of course be self-evident that the foot-operated means in question must be located out of the path of movement of the door A. 75 I offset the upper end 7 of the rod 6 so as to locate this end between the keeper 4 and the adjacent edge of the door A, thereby giving me compact association of the various parts.

If desired, a housing 14 may be carried by 80 the door A and provided with a coiled-spring 15 to assist in lifting the latch. This spring would also support the latch C in open position. It must be understood that the housing 14 and the spring 15 may be 85 dispensed with.

85 In the modified form of my contrivance shown in Figs. 2 and 3, the latch-lifter-rod 6' is mounted within the door-jamb casing 5', which is provided with a slot 16 through 90 which projects the offset end 7' of said rod. The outer end of the slot 16 is surrounded by a slotted plate 17 which is secured to the outer side of the door-jamb casing.

95 Keepers 18 are mounted within the door-jamb casing 5' to guide the rod 6'. The door-jamb casing is further provided with a slot 19 through which extends one portion of the foot lever 8' which is suitably pivoted to the bracket 10'.

100 The operation of my modified form of contrivance will be self-evident, and it will be seen upon referring particularly to Fig. 2 that the upper end 7' of the rod 6', as well as the foot lever 8' are located out of 105 the path of movement of the door A.

110 In contrivances of this class it is necessary that the latch-lifter rod 6 have a positive vertical movement, and without any pivotal connection with any operating parts, which

connections are bound to wear and frequently jam. In my disclosures, the latch-lifter rod merely rests in contact with its associated foot lever, and when the pressure of the foot is removed, the said latch rod of its own weight returns to normal position and without the assistance of any spring mechanism.

Obviously the shape of the various parts, 10 and their proportions, may be altered or changed, and the upper end of the rod 6 may be located on the opposite side of the keeper 4 to that shown, provided the latch C be made longer, without departing from the 15 spirit of my invention. But in all embodiments thereof the rod 6 must be located out of the path of movement of the door A.

What I claim is:

In combination a latch pivoted to a refrigerator door and the like and extending 20 beyond one side thereof; a keeper attached to the door-jamb frame; a latch-lifter rod adapted to be supported by said door-jamb frame to have vertical movement only, and provided at its upper end with a laterally 25 offset portion which operates adjacent one side of said keeper and underneath said latch, and a foot-operated lever against which the lower end of said rod rests, the said rod through its own weight returning 30 to normal position when pressure is relieved from said lever.

CECIL EDWARD DILLISTONE.
